EUGENE HOLT AND LAFAYETTE HOLT, OF BURLINGTON, NORTH CAROLINA.

YARN-BEAM.

1,175,953.

Specification of Letters Patent. Patented Mar. 21, 1916.

Application filed March 3, 1915. Serial No. 11,727.

To all whom it may concern:

Be it known that we, EUGENE HOLT and LAFAYETTE HOLT, citizens of the United States, residing at Burlington, in the county 5 of Alamance and State of North Carolina, have invented certain new and useful Improvements in Yarn-Beams, of which the following is a specification.

Our invention relates to an improvement 10 in yarn beams; and particularly to beams of the perforated cylinder type which are employed for holding yarn during dyeing, cleaning and other operations.

The primary object thereof is to provide 15 a yarn beam of durable and light construction which is both convenient and inexpensive to make and capable of being easily repaired in the case of damage or breakage.

A further object of our invention is to 20 provide a yarn beam that is constituted of detachable and interchangeable parts which can be readily assembled or dismounted; so that in case any of the elements become worn out or broken the same can be readily replaced and the beam thus put in condition 25 for further use.

The above objects and advantages of our invention will appear from the following description, taken in connection with the accompanying drawings, in which:

Figure 1 is a longitudinal section of our improved yarn beam; and Fig. 2 is an end elevation of the same.

In the particular description of our invention we employ the numerals 1 and 2 to indicate the heads or ends of our yarn beam, and it will be seen by reference to Fig. 1 that each of these heads has an annular groove 3 formed in one face, into which are 35 inserted the ends of the perforated body or cylinder 4 of the beam. This cylinder 4 and the heads 1 and 2 are held in fixed relation when the parts are assembled to form the beam, by means of tie rods 5; which run 40 lengthwise of the beam and are located inside the cylinder 4. These rods 5 pass through the heads 1 and 2, and are made fast at their outer ends, so that the heads 1 and 2 and the cylinder 4 can be securely 45 locked together. The grooves 3 will of course be of such width as to enable the cylinder 4 to fit snugly into the heads 1 and 2 and make a very compact and rigid structure.

As already shown in Fig. 1 the cylinder 4 is perforated over its entire extent, and

the perforations will be numerous and large enough for the purpose which the beam is designed to serve, as will be readily understood. The outer face of the cylinder will 60 be lined with a non-corrosive metal, such as lead, indicated at 6; and this lead lining will also extend over those portions of the faces of the heads 1 and 2 in which the grooves 3 are formed which are between the 65 grooves and the peripheral edges of the heads. By reason of this construction the cylinder 4 acts as a foundation body for supporting and reinforcing the softer yarn bearing surface of non-corrosive metal des- 70 ignated at 6. Of course the perforations in the cylinder 4 will extend through the lead lining on the cylinder also; and it will now be seen that when yarn is wrapped around the beam on the outer face of the cylinder 4 75 and between the heads, every part of the beam with which the yarn may come in contact will be properly lined, and even should certain parts of the beam become corroded by the action of chemicals when in use, the 80 corrosion will not injure the yarn because none of the corroded parts will be touched by it. In other words, the lead lining being non-corrosive, the chemicals will not affect this lining at all; and as a result the yarn 85 may be exposed to the action of the chemicals as much as is necessary in order to dye it, clean it or for any other purpose, without in the least being subjected to the risk of damage from any action that might take 90 place between the chemicals and certain parts of the beam construction.

The beam is, of course, mounted upon an operating shaft 7, which passes through the heads 1 and 2. We have shown the head 2 95 as being provided with a central boss or bearing 8, one end of which is engaged by a nut 9 on a threaded section 10 of the shaft 7; and a similar nut 9 and threaded section 10 are provided to enable the shaft to engage the head 1; whereby the beam and the shaft are secured firmly together. This head 1 has a central flange or boss 11 which carries a web 12 having a central opening 100 to accommodate the shaft 7 and a number of radial openings 13. The nut 9 at this end of the beam of course is screwed up tightly against the web 12; and the openings 13 give passage to liquid to and from the interior of the beam. If desired, radiating ribs 14 may be employed on the outer 105 surfaces of the heads or nuts 1 and 2 for the

purpose of strengthening or stiffening these heads and thus reduce the chance of bending or fracture.

In practice the beam will be mounted in the required position in a vat, or retort, for instance, which is employed in the various dyeing or other operations to which the yarn on the beam is to be subjected. The openings 13 will allow the dyeing liquids, etc., to pass to or from the inside of the beam, and the rotation thereof will keep the dye-stuffs and chemicals thoroughly mixed in a manner well known to those skilled in this art. The beam may be employed for either the inward or outward treatment for the yarn and the perforations in the cylinder 4 provide for the proper circulation of the dye stuffs and chemicals therethrough; so that all parts of the mass of yarn on the beam will be uniformly affected to the required extent.

From the above description it will be seen that our beam combines both compactness and strength; and by virtue of its sectional design it can be dismounted and taken apart with very little trouble in order to repair it or replace a broken or worn out part. It is exceedingly compact and very cheap to make and comprises relatively few parts. We wish to have it understood that the above description as well as the drawings are illustrative only; and we do not care to be limited to the exact details shown and described. On the contrary we reserve to ourselves the right to make such changes in the various parts as fairly fall within the scope and spirit of our invention.

What is claimed as new is:

1. A yarn beam including a pair of heads each having a recess therein, a foundation body having its ends received in said recesses, a yarn bearing surface supported on said foundation body, and means for rigidly holding said parts in assembled relation.
2. A yarn beam including a pair of heads

each having an annular groove in one face, a hollow perforated cylindrical foundation body having its ends received in said grooves, a yarn bearing surface supported on said foundation body and having perforations in registration with the perforations in said body, and means rigidly holding said parts in assembled relation.

3. A yarn beam including a pair of heads each having an annular groove in one face, a hollow perforated cylindrical foundation body having its ends received in said grooves, a yarn bearing surface supported on said foundation body and having perforations in registration with the perforations in said body, and tie rods passing through said heads and located within said foundation body to hold said parts in assembled relation.

4. A yarn beam comprising a pair of heads each having an annular groove in one face, a perforated cylinder having its ends fitting into said grooves, tie rods passing through said heads and located within the cylinder for securing the heads and cylinder together, one of said heads having a central boss or flange carrying a perforated web, and a shaft extending through said web and the opposite head and secured to said heads for operating said yarn beam.

5. A yarn beam including heads, a rigid continuous surface foundation body, a yarn bearing surface supported thereby, and means assembling said heads, body and surface.

In testimony whereof, we have signed our names to this specification in the presence of two subscribing witnesses this 8th day of February 1915.

EUGENE HOLT.
LAFAYETTE HOLT.
